UNITED STATES PATENT OFFICE.

JOHN H. MORROW, OF CHICAGO, ILLINOIS.

FISHING-TOOL FOR WELLS.

No. 832,920.

Specification of Letters Patent.

Patented Oct. 9, 1906.

Application filed March 28, 1904. Serial No. 200,260.

To all whom it may concern:

Be it known that I, JOHN H. MORROW, a citizen of the United States, residing at Chicago, county of Cook, State of Illinois, have 5 invented a certain new and useful Improvement in Fishing-Tools for Wells; and I declare the following to be a full, clear, and exact description of the invention, such as will enable others skilled in the art to which it 10 pertains to make and use the same, reference being had to the accompanying drawings, which form a part of this specification.

My invention relates in general to grappling-tools, and more particularly to a tool 15 for removing pipes, rods, or other articles from Artesian wells.

In the boring of Artesian wells it frequently happens that tools, rods, or sections of pipes become detached in the well and much 20 trouble is experienced in their removal owing not only to the difficulty in gripping the object, but also to the limited space requiring the use of a small tool which as heretofore constructed has been insufficient in structural strength to lift heavy objects.

The primary object of my invention is to provide a grappling-tool which may be lowered into a well and caused to engage any object therein that it is desired to remove from 25 the well and which may be at all times controlled by the operator, so that it may be disengaged from the object, if desired.

A further object of my invention is to provide a grappling device which will be simple 30 in construction, inexpensive in manufacture, and efficient in use.

My invention, generally described, consists in a pawl-carrier, means for lowering the carrier into a well, one or more vertically-40 swinging pawls pivotally supported in sockets formed in the carrier, means for swinging the pawl relatively to the carrier, and a support on the carrier below the pawl to relieve the strain on the pivot of the pawl when an 45 object is being elevated.

My invention will be more fully described hereinafter with reference to the accompanying drawings, in which the same is illustrated as embodied in two convenient and practical 50 forms, and in which—

Figure 1 is an elevational view, parts being shown in section; Fig. 2, a view similar to Fig. 1, showing the pawls in engagement with the surrounding pipe; Fig. 3, a sectional view on line 3 3, Fig. 2; Fig. 4, an elevational view of the tool removed from the pipe;

Fig. 5, a vertical sectional view of a modified embodiment of my invention; Fig. 6, a vertical sectional view in a plane at right angles to Fig. 5; and Fig. 7 a transverse section on line 7 7, Fig. 5.

Similar reference characters are used to designate similar parts in the several figures of the drawings.

Referring more particularly to Figs. 1, 2, 3, 65 and 4, reference-letter A designates a section of pipe which is to be engaged and elevated by the grappling device. B designates a carrier for the pawls C' and C². The carrier B may conveniently consist in a solid metal 70 post, at the lower end of which is a radially-projecting shoulder b³, the under side of which is provided with a conical surface B³.

b designates a coupling in screw-threaded engagement with the upper end of the carrier B and by means of which the carrier is lowered into and elevated out of the well.

The pawls C' and C² are seated in sockets formed in the carrier in any desired manner—such, for instance, as by milling. The sockets B' and B² are out of alignment and overlap at their inner ends. C designates a pivotal rod extending through holes in the overlapped inner ends of the pawls and supported at its opposite ends in the carrier. The holes 85 in the pawls through which the pivotal rod extends are sufficiently large to permit the inner ends of the pawls to bear against the walls of the sockets, thereby relieving the strain upon the pivot. The outer ends of the 90 pawls are beveled, so as to form sharp edges adapted to bite into the inner wall of the surrounding pipe. Any suitable means may be provided for controlling the vertical movement of the pawls—such, for instance, as 95 chains c' and c²—which extend from holes near the outer ends of the pawls and are united to a common chain c of such a length as to extend to the surface of the ground when the tool has been lowered the desired 100 depth into the well.

D designates a loose ring surrounding the carrier B immediately below the pawls and resting upon the shoulder b³.

The operation and manner of using the 105 embodiment of my invention above described are as follows: When it is desired to remove from the well a section of pipe A, the tool is lowered into the section, the pawls C' and C² being preferably held in the elevated 110 position shown in dotted lines in Fig. 1. When the tool is in position within the pipe-

section, the tension on the chain *c* is discontinued, thereby allowing the pawls to fall by gravity into the position shown in full lines in Fig. 1. The carrier is then pulled upwardly through power applied to any suitable connecting means united to the coupling *b*. The upward movement of the carrier causes the sharp ends of the pawls to bite into the pipe, as shown at *a a* in Fig. 2, thereby securely uniting the tool to the pipe, so that the latter may be removed from the well. It will be noticed in Fig. 2 that when the pawls are in their horizontal positions they rest upon the ring *D*, which serves as a support to relieve the strain upon the pivot of the pawls. The ring *D* owing to its loosely surrounding the carrier serves to guide the tool into the pipe as it assumes an inclined position when the portion thereof which projects around the shoulder *b*³ rests upon the edge of the pipe, and thereby facilitates the insertion of the tool in the pipe.

In Figs. 5, 6, and 7 I have illustrated a modified embodiment of my invention particularly adapted for removing rods or small pipes from a well. In such figures *A'* designates the pipe which forms the permanent wall of the well, while *E* designates a rod which it is desired to remove from the well. *F* is a pawl-carrier consisting in a horizontal ring and an upwardly-projecting portion *F*², rigidly secured to the ring. *f*² designates a rod secured to the portion *F*² of the carrier by means of which the carrier is lowered into and elevated from the well.

The inner surface of the ring of the carrier is cut away to form an annular shoulder *f*, which serves as a seat for a die *G*. The die *G* is removably held within the ring of the carrier by any suitable means—such, for instance, as clamp-screws *g*. The die *G* is provided with a central opening, at one side of which is a sharp biting edge *G'*.

H designates a vertically-swinging pawl pivotally supported in a socket *F'*, formed in the carrier. *h* designates a pivotal rod about which the pawl swings, the hole through which the rod extends being sufficiently large to permit the end of the pawl to bear against the wall of the surrounding socket. The portion of the die *G* beneath the pawl is provided with a recess which alines with the lower edge of the socket *F'* in the carrier, so that when the pawl assumes a horizontal position it will be supported upon the die, as clearly shown in Fig. 5.

Any suitable means may be provided for swinging the pawl relatively to the carrier—such, for instance, as a chain *h'*—which extends from the pawl, through an opening *f'* in the carrier, and thence upwardly to the surface of the ground.

The operation of the modified embodiment of my invention above described is as follows:

65 The carrier is lowered within the pipe *A'*,

forming the wall of the well by means of the rod *f*². When the carrier reaches the point where the rod *E* is located, the upper end of the latter is received within the opening through the die, after which the pawl *H* is allowed to swing into a horizontal position, so that the surface of the rod will be engaged at diametrically opposite points by the edge *G'* of the die and the pawl. The carrier may then be lifted out of the well and with it the rod *E*.

It will be noticed that in both of the illustrated embodiments of my invention a pawl is seated within a socket in a carrier and engages the wall of the socket and is provided with a support to relieve the strain upon the pivot of the pawl when it engages an object.

It will be further observed that in both embodiments of my invention the pawl is at all times under the control of the operator, so that it may be lifted upwardly and disengaged from the object should it be found necessary to do so.

In the embodiment of my invention (shown in Figs. 5, 6, and 7) a set of dies *G*, having graduated sizes of openings therethrough, may be employed, so that by changing the die the same tool may be used for removing pipes or rods of different diameters. The die *G* co-operates with the pawl *H* to cause the latter to tightly grip the pipe or rod *E*, while in the embodiment of my invention illustrated in Figs. 1 to 4 each pawl co-operates with the other to cause it to tightly engage the inner surface of the tube.

From the foregoing description it is evident that I have invented an improved lifting-tool especially adapted for use in removing pipes or rods from Artesian wells and which is simple and strong in construction and may be readily operated to grip an object and tightly hold the same while being elevated out of the well.

While I have described more or less precisely the details of construction, I do not wish to be understood as limiting myself thereto, as I contemplate changes in form, the proportion of parts, and the substitution of equivalents as circumstances may suggest or render expedient without departing from the spirit of my invention.

Having now fully described my invention, what I claim as new, and desire to secure by Letters Patent, is—

1. In a lifting-tool, the combination with a carrier, of a pawl vertically movably supported within a socket in said carrier and adapted to bear against the inner wall of the socket, means for raising and lowering said carrier, means for moving the pawl relatively to the carrier, and co-operating mechanism for causing the pawl to tightly grip an object.

2. In a lifting-tool, the combination with a carrier, of a pawl vertically movably sup-

130

ported upon the carrier; means for raising and lowering the carrier, means for moving the pawl relatively to the carrier, coöperating mechanism for causing the pawl to 5 tightly grip an object, and a shoulder upon which the pawl is supported and which relieves the strain upon the pivot of the pawl when an object is lifted.

3. In a lifting-tool, the combination with a 10 carrier, of a vertically-movable pawl loosely supported within a socket in the carrier, and adapted to engage the inner wall of the socket, a pivot-pin extending loosely through a hole in the pawl, means for raising and lowering said carrier, means for moving the 15 pawl relatively to the carrier, and coöperating mechanism for causing the pawl to tightly grip an object.

4. In a lifting-tool, the combination with a 20 carrier, of two oppositely radially projecting pawls vertically movably supported within sockets in the carrier, the inner ends of the pawls adapted to bear against the inner walls of the sockets, means for raising and lowering the carrier, and means for moving the 25 pawls relatively to the carrier.

5. In a lifting-tool, the combination with a 20 carrier having a radially-projecting shoulder, of a pawl vertically movably supported upon the carrier, means for raising and lowering the carrier, means for moving the pawl relatively to the carrier, coöperating mechanism for causing the pawl to tightly grip an object, and a ring loosely supported upon the

shoulder of the carrier and projecting radially around the carrier upon which the pawl rests and which coöperates with said shoulder to relieve the strain upon the pivot of the pawl when an object is elevated.

6. In a lifting-tool, the combination with a 40 carrier having a radially-projecting shoulder, of two oppositely radially projecting pawls vertically movably supported within sockets in the carrier, means for raising and lowering the carrier, means for moving the pawls relatively to the carrier, and a ring loosely supported upon said shoulder and projecting radially around the carrier upon which the pawls rest and which coöperates with said shoulder to relieve the strain upon the pivot 45 of the pawls when an object is elevated.

7. In a lifting-tool, the combination with a carrier having overlapping radially-projecting sockets therein, of two oppositely-projecting pawls supported within said sockets, 55 a rod extending loosely through holes in the inner ends of the pawls, means for raising and lowering the carrier, means for moving the pawls relatively to the carrier, and a ring loosely supported by and projecting radially 60 around the carrier upon which the pawls rest when an object is lifted.

In testimony whereof I sign this specification in the presence of two witnesses.

JOHN H. MORROW.
